DISPLAY STRUCTURES

Charles A. Decker, Jersey City, N. J., assignor to Arvey Corporation, Chicago, Ill., a corporation of Illinois

Application January 30, 1953, Serial No. 334,228

5 Claims. (Cl. 40—124.1)

This invention relates to display structures adapted for advertising purposes, and more particularly to a structure which may be printed or lithographed on both sides thereof.

An object of the invention is to provide a display structure adapted to be collapsed to a flat knockdown condition suitable for shipping and/or storage.

Another object of the invention is to provide a display structure having a base adapted to be readily opened and automatically locked in its distended condition to provide a support for an upright panel.

A further object of the invention is to provide a display structure in which the base is secured in its open position by means of locking flaps hingedly connected to the base for abutting engagement with attachment flaps provided on the base for fixed engagement against opposite sides of the panel.

Another object of the invention is to provide a display structure adapted to be formed of two blanks of sheet material, such as cardboard, cut, scored and secured together to provide a display panel supported in upright position by a base having pockets in opposite sides thereof to receive pamphlets, leaflets, etc., for distribution to customers.

Another object of the invention is to provide a display structure in which the base comprises support walls hingedly connected to opposite sides of the display panel and diverging downwardly therefrom when in open set-up position, the support walls being secured in their open position by brace walls hingedly connected to their respective support walls and to each other.

Another object is to provide a display structure in which the brace walls engage the display panel and coat with the support walls to maintain the panel in an upright position.

This invention embodies other novel features, details of construction and arrangement of parts which are hereinafter set forth in the specification and claims and illustrated in the accompanying drawings, wherein:

Fig. 1 is a front elevational view illustrating a display structure embodying features of the present invention.

Fig. 2 is a side elevational view of same.

Fig. 3 is a top plan view of same.

Fig. 4 is a fragmentary front elevational view, partly in section, illustrating the display structure.

Fig. 5 is a fragmentary end elevational view showing the display structure in collapsed form.

Fig. 6 is a plan view illustrating a blank of sheet material cut and scored to form the base of the display structure.

Fig. 7 is a plan view showing the display panel as blanked from sheet material.

Referring now to the drawings for a better understanding of the invention, the display structure is shown as comprising a display panel 2 and a base 4 formed from sheet material, such as cardboard, fiberboard, or the like, the panel being flat and formed at its lower end with a tongue 6 having oppositely extending ears 8—8.

2

As illustrated in Fig. 6, the base blank 10 is scored along lines 12 and 13 to form attachment flaps 14 and 15 hingedly connected to support walls 16 and 17, respectively. The blank is also scored along lines 18, 19 and 20 to form brace walls 21 and 22 hingedly connected to adjacent support walls and to each other. The brace wall 21 is cut at 23 and scored at 24 to form a hinged locking flap 26, and the brace wall 22 is cut at 27 and scored at 28 to form a hinged locking flap 29. The free ends of the locking flaps 26 and 29 are cut off to provide flat edges at 30 and 31, respectively. A slot 32 is formed in the blank 10 along the score line 19 to receive the panel tongue 6.

Apertures 33 and 34 are formed in the support walls 16 and 17, respectively. The lower end of the panel 2 is secured to the attachment flaps 14 and 15 by means of adhesive and/or staples 36, the flaps being disposed on opposite sides of the panel and projecting downwardly for abutting engagement with the free ends of the locking flaps 26 and 29 when the display structure is in its set-up condition, as illustrated in Figs. 1 to 4 in the drawings. When the display structure is collapsed, the locking tongues 26 and 29 lie flat between their related attachment flaps 14 and 15 and support walls 16 and 17, as illustrated in Fig. 5.

The panel tongue 6 projects downwardly through the slot 32 in the base 4 to maintain the panel 2 in fixed upright position upon the base, and the ears 8—8 on the tongue engage the hinge portion 19 to limit the downward movement of the brace walls 21 and 22 and thereby limit the pivotal movement of the support walls 16 and 17 away from the panel.

In setting up the display structure, the support walls 16 and 17 are pivoted away from each other until the brace walls 21 and 22 move into engagement with the abutment ears 8—8, thus preventing further outward pivotal movement of the support walls relative to the panel 2. During downward movement of the brace walls 21 and 22, the flat edges 30 and 31 of the locking flaps 26 and 29, respectively, move into abutting engagement under the lower edges of the attachment flaps 14 and 15, respectively, to prevent upward movement of the brace walls and inward pivotal movement of the support walls.

To collapse the display structure to a flat form suitable for shipment and/or storage, the locking flaps 26 and 29 are pivoted out of engagement with their respective attachment flaps toward their adjacent support walls to permit the brace walls to be moved upwardly to draw the support walls toward each other into parallel relationship, as illustrated in Fig. 5 in the drawings.

When the display structure is in set-up distended condition, it will be noted that pamphlets may be disposed within the apertures 33 and 34 in the support walls 16 and 17, respectively, for withdrawal therefrom by persons interested in obtaining further information relating to the product being advertised by the display structure.

While this invention has been shown in but one form, it is obvious to those skilled in the art that it is not so limited but is susceptible of various changes and modifications without departing from the spirit and scope of the claimed invention.

I claim as my invention:

1. In a display structure, a panel formed from flat sheet material to provide a depending tongue having an abutment ear thereon, a base cut and scored from flat sheet material to provide attachment flaps secured to opposite sides of the panel and spaced above said abutment ear, support walls hinged to the upper edges of the attachment flaps and diverging downwardly therefrom, brace walls hinged together in the plane of the panel tongue to rest upon the abutment ear and diverging downwardly and hinged to their related adjacent support walls, and

locking flaps hinged to the brace walls with their free ends in abutting engagement under the lower edges of the attachment flaps to prevent upward movement of the brace walls, the juncture of the brace walls being slotted to receive said tongue.

2. A structure according to claim 1 in which the brace walls are cut and scored to form hinged locking flaps converging upwardly into engagement against opposite sides of the panel tongue and in abutting engagement with their respective attachment flaps.

3. A display structure comprising a flat panel and a base, said panel having a depending tongue of greater width than length, said tongue having oppositely projecting abutment ears adjacent the lower end thereof, said base comprising a blank of sheet material cut and scored to form hingedly connected brace walls, support walls hinged to related brace walls, and attachment flaps hinged to related support walls and secured to opposite sides of said panel adjacent said tongue with their free ends downwardly disposed, said tongue projecting downwardly through a slot formed at the juncture of the brace walls, said ears engaging the underside of and supporting the brace walls, and locking flaps hinged on the brace walls in abutting engagement with the free ends of the attachment flaps.

4. A display structure comprising a flat panel and a base, said panel having a depending tongue of greater width than length, said tongue having oppositely projecting abutment ears adjacent the lower end thereof, said base comprising a blank of sheet material cut and scored to form hingedly connected brace walls, support walls hinged to related brace walls, and attachment flaps hinged to related support walls and secured to opposite sides of said panel adjacent said tongue with their free ends downwardly disposed, said tongue projecting downwardly through a slot formed at the juncture of the brace walls, said ears engaging the underside of and supporting

the brace walls, and locking flaps hinged on the brace walls in abutting engagement with the free ends of the attachment flaps, said support and brace walls being inclined downwardly and outwardly from the plane of the panel.

5. A display structure comprising a flat panel and a base, said panel having a depending tongue of greater width than length, said tongue having oppositely projecting abutment ears adjacent the lower end thereof, 10 said base comprising a blank of sheet material cut and scored to form hingedly connected brace walls, support walls hinged to related brace walls, and attachment flaps hinged to related support walls and secured to opposite sides of said panel adjacent said tongue with their free 15 ends downwardly disposed, said tongue projecting downwardly through a slot formed at the juncture of the brace walls, said ears engaging the underside of and supporting the brace walls, and locking flaps hinged to the brace walls in abutting engagement with the free ends of the attachment flaps, said support and brace walls being inclined 20 downwardly and outwardly from the plane of the panel, said support walls having apertures adjacent said locking flaps to receive sheets of advertising material adapted to engage and prevent pivot movement of the locking flaps away from the attachment flaps.
